BLOWOUT PREVENTER

Arthur J. Penick and Kirby T. Penick, Houston,
Tex.

Application December 9, 1937, Serial No. 178,843

2 Claims. (Cl. 251—159)

This invention relates to a blowout preventer.

An object of the invention is to provide a blowout preventer of the ram type for forming a fluid tight seal between the outer casing and a the drill stem or other inner pipe in a well.

It is another object of the invention to provide a blowout preventer of the character described equipped with resilient packing material which will completely surround the inner pipe, when the rams are in active position and form a fluid tight seal therewith and which will also form continuous seals between the rams and the preventer casing around the opening for the inner pipe through said casing.

A further object of the invention resides in the provision of a novel type of blowout preventer having rams of such construction that the sealing material may from time to time be subjected to compression, as required, to take up the wear to which the packing material is subjected so as to constantly maintain said seals.

The invention embodies, in a blowout preventer, a novel type of ram more specifically hereinafter described.

With the above and other objects in view the invention has particular relation to certain novel features of construction, operation and arrangement of parts, an example of which is given in this specification and illustrated in the accompanying drawings, wherein—

Figure 1 shows a vertical, sectional view of the blowout preventer showing an inner pipe therein with the rams in active position to form a fluid tight seal between the inner pipe and the outer well casing.

Figure 2 shows a horizontal, sectional view showing one of the rams partly broken away.

Figure 3 shows a vertical, sectional view taken on the line 3—3 of Figure 2, with the sealing material removed, and

Figure 4 shows a plan view.

Referring now more particularly to the drawings wherein like numerals of reference designate the same parts in each of the figures, the numeral 1 designates an outer well casing to the upper end of which the casing of the blowout preventer is attached. As illustrated the blowout preventer casing is substantially rectangular in cross-section with its bottom 2 and top 3 approximately parallel and having the parallel side walls 4, 4. The outer ends of the preventer casing are closed by the end plates 5, 5 which may be bolted thereto as more accurately shown in Figures 1 and 4. The preventer casing has a tubular T-connection 6 whereby it may be con-

nected to the well casing 1 and leading out from the connection 6 there is the usual flow line 7. The top 3 of the preventer casing is provided with a circular opening 8 to permit the passage of the inner pipe or drill stem 9 therethrough.

On opposite sides of the inner pipe, and mounted in the preventer casing are the complementary rams designated generally by the numerals 10, 10. The rams are of similar construction. Each ram embodies a retainer 11 for the sealing means or 10 packing. This retainer embodies a rectangular bottom 11a, to ride on the bottom of the preventer casing, the side walls 11b, to ride against the sides of the preventer casing, and the outer end wall 11c. Each ram also includes a cover 15 plate 12. The inner margins of the bottom 11a and the cover 12 are arcuate as shown in Figures 2 and 4 to conform to the shape of and to surround the inner pipe 9. The retainer 11 is therefore movable radially relative to the corresponding cover plate 12. The plate 12 has the depending stops 13, 13 at its outer margin against which the end wall of the corresponding retainer engages, when the rams are moved to inactive position so as to cause the plates 12 to also move 25 outwardly to inactive position. The bottom of each retainer is formed with an arcuate groove 14, said groove registering when the rams are moved to active position so as to form a continuous circular groove all the way around the opening through the preventer casing and the upper side of the cover plates 12 have similar grooves 15 which similarly register when the rams are in active position. The grooves 14 and 15 have the spaced openings 16 and 17 from the interior 30 of each retainer into the corresponding grooves. The retainers are filled with a sealing material 18 formed of rubber or other suitable resilient material and this material is molded through the openings 16, 17 and into the grooves 14, 15 so as 35 to fill the latter thus forming the lower and upper packing rings 19, 20 which form seals with the bottom and top, respectively, of the preventer casing all around the opening therethrough for the inner pipe, when the rams are in active position.

It will be noted that the inner ends of the rams are completely open and the sealing material is exposed through said open inner ends and is formed arcuate to conform to the shape of and 50 to fit closely around the inner pipe, or drill stem to form a seal therewith when the rams are in said active position.

The end plates 5 of the preventer casing are provided with internally threaded bosses 21, 21

through which the shafts 22, 22 may be threaded and the inner ends of these shafts have swiveling connections with the end plates 11c of the respective retainers, as more accurately shown in Figures 1 and 2, whereby the rams may be moved outwardly into inactive position or inwardly into active position.

Mounted on the inner margins of the bottom 11a of each retainer there is an arcuate retainer plate 23 shaped to fit closely about the inner pipe when the rams are in active position. These retainer plates 23 are slidably mounted and extended inwardly beyond the inner margins of the corresponding bottoms 11a of the retainers. They are provided with spaced openings 24 through which the sealing material is molded to tie them in place.

In operation when a blowout is threatened the shafts 22 may be turned by any suitable means provided for the purpose so as to move the rams inwardly into active position around the inner pipe and the sealing material 18 will completely surround and fit closely against said inner pipe to form a fluid tight seal therewith. At the same time packing rings 19 and 20 will form seals all around the preventer casing opening with the bottom and the top, respectively, of said preventer casing. The inner margins of the cover plates 12 and the retainer plates 23 will also be in contact with the inner pipe. If a leak should develop the retainers 11, 11 may be forced further inwardly placing the sealing material 18 under compression and forcing it more closely about the inner pipe 9. As the sealing material is placed under compression it will flow through the openings 16, 17 into the grooves 14, 15 placing the material in said grooves under compression and forming fluid tight seals between the rams and the bottom and top 2 and 3, of the preventer casing so as to form continuous seals between the rams and preventer casing all the way around the opening through said casing.

As compression is applied to the sealing material 18 the retainers 11 will move inwardly but the cover plates 12 and the retainers 23 being already in contact with the inner pipe will remain stationary. This inward movement of the re-

tainers is permitted because the inner margin of each bottom 11a is spaced outwardly from the inner pipe as is more clearly shown in Figure 1.

The drawings and description disclose what is now considered to be a preferred form of the invention by way of illustration only, reserving the right to make such mechanical changes as will not depart from the principle of the invention as defined by the appended claims.

What we claim is:

1. In a blowout preventer a movable ram comprising a retainer having side walls, an outer end wall and a bottom all joined together as a unit, the inner margin of the bottom being arcuate, an independent cover plate on the retainer whose inner margin is arcuate, a retainer plate seated on the bottom whose inner margin is arcuate and extends inwardly beyond the corresponding margin of the bottom, resilient material filling the retainer and forming sealing means and whose inner end is exposed, said cover plate, retainer plate and bottom having openings through which the resilient material is molded whereby to unite the retainer, retainer plate and the cover plate together as a unit.

2. A blowout preventer comprising a casing having an opening therethrough to receive an inner pipe, complementary rams in the casing whose inner ends are shaped to fit closely around the inner pipe when in active position, each ram comprising a retainer having side walls, an outer wall and a bottom all joined together as a unit, the inner margin of the bottom being arcuate, an independent cover plate on the retainer whose inner margin is arcuate, a retainer plate seated on the bottom whose inner margin is arcuate and extends inwardly beyond the corresponding margin of the bottom, resilient material filling the retainer and forming sealing means and whose inner end is exposed, said resilient material being incorporated with the cover plate, retainer plate and bottom whereby to unite the retainer, retainer plate and cover plate together as a unit.
